UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

SERVICE-METER APPARATUS FOR TELEPHONE-EXCHANGES.

No. 799,760.

Specification of Letters Patent.

Patented Sept. 19, 1905.

Application filed February 23, 1904. Serial No. 194,801.

To all whom it may concern:

Be it known that I, CHARLES E. SCRIBNER, a citizen of the United States, residing at Jericho, in the county of Chittenden and State 5 of Vermont, have invented a certain new and useful Improvement in Service-Meter Apparatus for Telephone-Exchanges, of which the following is a full, clear, concise, and exact description.

10 My invention relates to service-meter apparatus for telephone-exchanges; and its object is in general to provide improved and simplified apparatus and an improved organization of circuits whereby a record may be 15 made of each call from a subscriber's station which is answered and the desired connection established at the central office.

15 My invention particularly contemplates a service-meter which will be adapted for use 20 on party-lines and in exchanges where coin-collectors, as well as service-meters, are employed as toll devices.

25 The accompanying drawings illustrate a service-meter apparatus and circuits therefor constructed and organized in accordance with my invention, and I will describe the same particularly by reference to said drawings, reserving for the appended claims a statement 30 of the parts, improvements, or combinations considered to be novel.

35 In the drawings, Figure 1 is a diagram illustrating, by means of conventional symbols, the apparatus and circuits of a telephone-line extending from a subscriber's station to a central office of a telephone-exchange. Fig. 2 is a plan view of the service-meter which is provided at the subscriber's station with the containing case in section. Fig. 3 is a vertical 40 sectional view of the service-meter on line 3 3 of Fig. 2.

The same characters of reference are used to designate the same parts wherever they are shown.

Referring to Fig. 1, the telephone-line extends in two limbs or line conductors 4 5 from the subscriber's apparatus S to the central switchboard C, where it is provided with the usual spring-jack terminals a a. One pole of the central battery b is connected to earth 45 and the other or free pole is connected to the limb 4 of the telephone-line through the winding of the line-relay c and the contacts of the cut-off relay d. The other limb 5 of the tele-

phone-line is normally open at the central office. The line-relay c controls a line-signal 55 lamp c' in a local circuit.

A portion of the usual operator's plug circuit, by which connection is made with the line, is illustrated. The tip and ring contacts of the plug form the terminals of link conductors 6 7, respectively, which are brought into connection with the conductors 5 4, respectively, when the operator's plug p is inserted in the spring-jack of the telephone-line. At the same time the cut-off relay is excited by 65 current in a local circuit 8 in accordance with the usual practice.

The operator's supervisory relay e is included in the link conductor 6 between the grounded pole of the battery and the tip of 70 the plug. This supervisory relay controls a supervisory lamp e', as usual.

The plug - circuit shown is of the type which is adapted to be used in telephone-exchange systems having coin-collectors at the 75 subscribers' stations, and is therefore provided with two keys f and g, by which the operator is enabled to actuate the mechanism of the subscriber's toll device. The key f is adapted when actuated to break the continuity of conductors 6 7 and connect both the ends thereof leading to the plug p with the free pole of a grounded generator G. Similarly, the key g when actuated is adapted to break the continuity of the conductors 6 85 7 and to connect the end of conductors 7 only to the free pole of a grounded generator G', the conductor 6 being simply opened. In practice for systems where coin - collectors as well as service-meters are employed the 90 free pole of one of the generators will be positive, while the free pole of the other generator will be negative; but this is not necessary for the operation of the service-meter herein described.

95 The subscriber's station is equipped with the usual telephone transmitting and receiving apparatus, with a telephone-switch h controlling the circuits thereof, and in addition there is provided the service-meter k, the 100 mechanism of which is shown in detail in Figs. 2 and 3. The register or counting train l is provided with a driving ratchet-wheel r, which is arranged to be actuated by a pawl o, carried by the armature m' of the 105 magnet m. The armature m' may be termed

a "two-step" armature—that is to say, its attractive movement toward the magnet-core is divided into two steps or stages. A contact-spring *s* is arranged to be engaged 5 by the armature when the same is partially attracted, so that the further attractive movement of the armature will be opposed by the tension of said spring. The initial attractive movement may be opposed similarly 10 by the weight of the armature. The pawl *O* is arranged to engage the ratchet-wheel *r* only during the final attractive movement of the armature, the initial movement being completed without advancing the counting-train. A manual switch-key *t*, which may control the connection of the service-meter magnet, is associated with said magnet. This switch-key is adapted to be set manually, but is arranged to be released 15 in the initial attractive movement of the armature *m'* simultaneously with or shortly after the engagement of the armature with the contact-spring *s*.

The manual switch may consist of a plunger *t'*, arranged to be operated manually 20 against the tension of a coil-spring *t''*, and the armature *m'* may carry a detent *m²*, which is adapted to engage a notch or offset of the plunger to latch the same in its actuated position. The pawl *m²* normally rests upon a 25 piece of insulating material *t'*, carried by the plunger; but when the plunger is depressed the pawl *m²* comes into electrical contact with the metallic portion thereof at the notch or offset. The contact thus made serves to 30 complete the connection of a branch 9 from conductor 4 to ground, said branch including the magnet *m*, the plunger *t* being connected with said conductor and the magnet being 35 connected between the armature *m'* and ground. The armature *m'* in its initial attractive movement makes contact with the spring *s*, which is connected with the other limb 5 of the telephone-line and at the same 40 time or shortly after the switch-key is released, so that the connection of the magnet is thus transferred from one line conductor 4 to the other line conductor 5. If the armature goes on and takes the second step to 45 complete its attractive movement, the counting-train *l* also will be advanced by the pawl engaging the ratchet-wheel *r*. The magnet *m* is wound to respond to currents from the 50 generators *G G'*, but is unresponsive to current from the battery *b* of lower electromotive force.

It should be stated that while for convenience of illustration two batteries (marked *b*) are shown in the drawings it is understood, of course, that these may be one and the same battery in accordance with the usual practice.

The system of circuits above described forms no part of the present invention, but is

claimed in a divisional application, Serial No. 65 244,355, filed February 6, 1905.

The operation of the system is very similar to the operation of the system where coin-collectors are employed—such, for example, as the system of Patent No. 665,874, issued 70 January 15, 1901, to A. M. Bullard. Indeed, the working of the system from the central office operator's standpoint is identical.

In exchanges where the number of calls from a given station determines the amount 75 to be paid by the subscriber for telephone service the system may be organized upon either of two plans: the subscriber may pay for each call as he makes it by actually depositing a coin in the coin-collector or in place 80 of the coin-collector each call may be recorded upon a register or meter and payment made in a lump sum at the end of a given time for the number of calls recorded. The subscriber should of course be charged for 85 service only when the connection called for is actually obtained, and in the system of the Bullard patent, before referred to, the coin-collector receives the coin provisionally, and the operator may by pressing the proper one 90 of two keys bring about the actuation of the mechanism to return the coin to the subscriber or deposit it in the cash-box, according to circumstances.

It is sometimes desirable that an exchange 95 be equipped partially with call-recording devices and partially with coin-collectors, as subscribers may prefer. It may be that a party-line will have some of its substations 100 equipped with coin-collectors, while other substations of the same line will have service-meters instead.

Lines of such differing character are frequently grouped together indiscriminately 105 at the central-office switchboard, and the operator, who must do the work of establishing and taking down connections almost mechanically, should not be burdened with the mental effort of distinguishing between lines having different classes of toll devices. It is 110 an especial advantage of the service-meter apparatus of the present invention that it may be used in systems where coin-collectors are also employed, such as the system of the Bullard patent, without requiring any different apparatus at the central office or any different action by the operator.

The call is transmitted to the central office in the Bullard system by the subscriber depositing a coin in the toll-box. In the present system the call is transmitted by the subscriber actuating his manual switch-key *t*. The effect in either case is to cause the display of a line-signal at the central office to which the operator responds by plugging 115 into the spring-jack of the calling-line. The operation of the toll device is then determined by two keys in the operator's plug- 120

circuit. If the desired connection is obtained, the "charge-key" is depressed, which in the case of the coin-collector causes the coin to be deposited in the cash-box and in 5 the case of the service-meter causes the call to be recorded upon a register. If for any

reason no charge is to be made, as where the desired connection cannot be established, the operator actuates the release-key, which 10 in the case of the coin-collector causes the coin to be returned to the subscriber and in the case of the service-meter causes the mechanism to be restored without actuating the register.

15 To describe the operation of the system of this invention more in detail, it will be seen that depressing the switch-key *t* at the subscriber's station will complete a branch circuit 9 to earth from limb 4 of the telephone-line. A circuit is thus completed from the central battery *b*, through the line-relay *c* and over conductors 4 and 9 to earth, whereby the line-relay is excited and causes the display of the line-signal lamp *c'*. The mag- 20

net *m* of the service-meter, although included in this circuit, does not respond to current from the battery *b*. The switch-key *t* being once depressed is latched in its actuated position by the pawl *m'*, carried by the armature *m'* of the magnet. The operator answers the call by plugging into the spring-jack *a* of the line, as usual, and at the proper time, which is preferably after the "disconnect-signal" is received at the end of the con- 25

versation, depresses one or the other of the keys *f* *g*, according to circumstances. If no charge is to be made, the key *g* will be depressed, which will cause the armature of the subscriber's service-meter magnet to take 30 only the initial step of its attractive movement, releasing the switch *t*, but not actuating the registering-train. If a charge is to be entered, the key *f* will be depressed, and this will bring about a complete attractive 35 movement of the armature *m'* instead of the mere half-step, and the registering-train *l* will be advanced to record the connection, the switch *t* being also released.

The control of the keys *f* *g* over the subscriber's service-meter is as follows: The key *g* applies current from generator *g'* to the limb 4 of the line, and this current flows to earth through the branch 9, containing the magnet *m*, said branch being closed by the 40 contact between the pawl *m'* and the plunger *t'* of the switch. The magnet will therefore be excited; but the armature in taking the first step in its attractive movement withdraws the detent *m*² from engagement with 45 the offset on the plunger, whereby the plunger is released and returned to its normal position by spring *t*², the connection of the magnet with conductor 4 being thus broken. The armature is now in contact with spring *s*, and 50 the connection of the magnet *m* is thus trans-

ferred to the other side of the telephone-line; but current having been applied by key *g* to the limb 4 only the magnet *m* is no longer energized, but permits its armature *m'* to drop back before the pawl *o* has advanced the 55

registering-train. When the key *f* is depressed, current from the generator *G* is applied to both conductors 4 5, so that although the first step in the movement of the magnet-armature breaks 60 the connection of the magnet with conductor 4 the magnet will receive current from conductor 5 by way of contact-spring *s*. Under these conditions the armature *m'* will complete its attractive movement and advance 65 the registering-train by means of the pawl *o* and the ratchet-wheel *r*. It will thus be seen that the magnet is adapted to be connected progressively with different actuating-circuits by switching mechanism controlled 70 by its own armature and that a movement of said armature through one or more steps may be brought about by applying current to one or more of said actuating-circuits.

I claim—

1. A service-meter comprising a registering-train, an electromagnet and an armature provided with a pawl for advancing said registering-train, in combination with a manual switch-key and a detent controlled by said 75 armature adapted to latch said switch in its actuated position, said detent being moved to release the switch in the movement of said armature.

2. The combination with an electromagnet and a two-step armature therefor, of a manual switch-key, an automatic latch for said switch-key arranged to be moved to release said key by the initial attractive movement of said armature, and a registering-train connected with said armature and arranged to be advanced in the final attractive movement thereof.

3. The combination with a service-meter having a counting-train, step-by-step mechanism for advancing said train and an electromagnet and armature for actuating said mechanism, of a switch-key adapted for manual operation and a latch for said switch-key controlled by said electromagnet.

4. In a service-meter, the combination with a counting-train, of an electromagnet having an armature and means actuated by a complete attraction of said armature for advancing said counting-train, a manual switch-key, and a latch for said switch-key controlled by said armature, said latch being withdrawn to release the switch-key in the initial movement of said armature, before the counting-train is advanced.

5. The combination with a registering-train, of an electromagnet and an armature therefor, a pawl actuated by said armature, adapted to advance said registering-train in the final attractive movement thereof,

initial attractive movement of the armature being independent of said registering-train, a manual switch-key and a detent carried by said armature adapted to latch said switch-key in its actuated position, said detent being moved to release said key in the initial attractive movement of said armature.

In witness whereof I hereunto subscribe my name this 20th day of January, A. D. 1904.

CHARLES E. SCRIBNER.
